TELEVISION ANTENNA OR SIMILAR ARTICLE

Andrew Colton, Wayne County, Mich.

Application December 23, 1957, Serial No. 48,984

Term of patent 14 years

(Cl. D26—14)

Fig. 1 is a side elevational view of a television antenna or similar article, showing my new design; the opposite side being substantially a mirror image thereof;

Fig. 2 is a top plan view; and

Fig. 3 is a side elevational view rotated at ninety degrees from the position shown in Fig. 1, the opposite side being substantially a mirror image thereof.

The broken line showing of a representative lamp shade and base in Fig. 1 is for illustrative purposes only.

I claim:

The ornamental design for a television antenna or similar article, as shown and described.
